WESTERN ELECTRIC COMPANY, INCORPORATED, OF NEW YORK, N. Y., A CORPORATION OF NEW YORK.

CALL-DISTRIBUTING SYSTEM.

1,299,558.

Specification of Letters Patent.

Patented Apr. 8, 1919.

Application filed March 24, 1917. Serial No. 157,089.

To all whom it may concern:

Be it known that we, GERALD DEAKIN, a citizen of the United States, and LIPA POLINKOWSKY, a subject of the Emperor of Russia, both residing at London, England, have invented certain new and useful Improvements in Call-Distributing Systems, of which the following is a full, clear, concise, and exact description.

10 This invention relates to call distributing systems for telephone exchanges, and more particularly to systems in which calls may be extended to an operator's position depending upon the busy or idle condition of such operator as electrically indicated by apparatus associated with such position.

The principal feature of the invention resides in the arrangement of the circuits and apparatus in such a manner that when a call has been extended to an operator, such operator's position will be maintained busy and therefore unconnectible to all subsequent calls during a predetermined period of time, such busy condition or guard being then removed so that another call may be extended to her position even though she has not as yet completed her duties in connection with the first mentioned call. In practice, the time interval will be of such extent that it is slightly less than the time in which the operator under normal conditions attends to her duties with regard to a call extended to her position, the time interval being such that after the busy condition or guard has been removed from the operator's position the usual automatic apparatus, by which the call is extended to such operator's position, will have sufficient time to operate to extend the call to the position before the operator has completed her duties with regard to the call first extended to her position, thereby expediting the connection and eliminating the usual waiting time occupied by the operation of the automatic apparatus between the instant when the operator is no longer busy with the previous call and the instant when the subsequent call is actually connected to her position.

Further features of the invention will 50 sufficiently appear from a description of one embodiment thereof hereinafter given.

In the drawings:

Figures 1 and 1^a, when placed side by side, represent diagrammatically so much

of a telephone exchange system as is required to illustrate the invention; and

Fig. 2 illustrates schematically one arrangement, for distributing calls to different operators, in which the busy condition or guard is maintained upon an operator's position and removed at the desired time.

Referring to Fig. 1, 3 represents a telephone line terminating in a group of first line finders, one of which is indicated at 4, and having associated therewith the usual line relay 5, energized upon the initiation of a call to place selectable potential in the usual manner upon the test terminal 6 of such line where it appears in the first line finder 4, and energizing the pilot or starting relay 7 common to the group of lines in which such line appears. The energization of the relay 7 closes a circuit for the power magnets 8 of all of the first line finders of the group indicated which are idle, that is, of which the relays 9 and 10 are de-energized. All of such idle first line finders thereupon start in motion to select and seize the calling line in the usual manner. Immediately that the brush 11 of one of such line finders makes contact with the terminal 6, the relay 12 is energized, placing a busy guard upon such terminal 6 by the closure of the circuit to ground through the low resistance right-hand winding of such relay 12, and when the interrupter 13 of such line finder is opened, as the brushes of such line finder are centered upon the terminals of the calling line, the shunt through such interrupter around the relay 9 is removed and such relay energizing, the circuit of the power magnet 8 is opened, and the circuit of the holding magnet 14 of such line finder is closed and the line finder brought positively to a stop with its brushes in contact with the terminals of the calling line. The energization of the relay 9 has closed a circuit in series with the circuit for the holding magnet 14 for starting a pilot relay 15 common to the group of trunk lines terminating in a given set of second line finders 16.

Assuming that the operator to whose position the connecting circuit 17 is individual is idle, a circuit will be established by the energization of such relay 15 over the sequence switch contact 72, sequence switch contact 62 to the relays 18 of all such as are idle of said connecting circuits.

Before proceeding farther it will be noted that all of the sequence switch contacts shown in the upper part of Figs. 1 and 1^a form a part of and are operated by the sequence switch 60 shown to the right of Fig. 1^a. Those sequence switch contacts shown within the dotted area in which the sequence switch 70 is shown form a part of and are operated by such sequence switch. 5 10 Similarly, those sequence switch contacts shown within the area delimited by the dotted line in which the sequence switch 80 is shown form a part of and are operated by such sequence switch, and those 15 shown within the area in which the sequence switch 80 is shown form a part of and are operated by such sequence switch. These switches are of well-known construction and their mode of operation being known 20 will not be described in detail herein.

Upon the energization of the relay 18 a circuit is closed over its armature and front contact, armature and back contact of the relay 19, sequence switch contact 63, to the power magnet 20 of the second line finder 16 to which the connecting circuit 17 is connected. Such second line finder thereupon starts in motion searching for the selectable potential which has been placed upon the 25 test terminal 21 of the trunk 22, extending from the first line finder 4 by the energization of the relay 9 in the usual manner. As soon as the test brush 23 reaches the terminal 21, a circuit is completed over the sequence switch contact 65, right-hand winding of the relay 24, sequence switch contact 82 to energize such relay 24, which thereupon places the usual busy guard upon the terminal 21 by the closure of the low resistance circuit through its left-hand winding. 30 As soon as the brushes of the line finder 16 are centered upon the terminals of the trunk 22 the shunt circuit around the relay 19 is opened by the interrupter 25, and such 35 relay 19 is energized, opening the circuit of the power magnet 20 and closing in the usual manner the circuit of the holding magnet 20' of the line finder 16 to stop such line finder in the usual manner with its 40 brushes properly centered upon the terminals of the trunk 22.

The energization of the relay 19 also closed circuits to energize the relay 26 and the power magnet of the sequence switch 55 60. Sequence switch 60 is driven from its first or normal position and under the influence of the local sequence switch contact 61 moves into its fourth position. The energization of the relay 26, which is maintained 60 until the sequence switch 60 has moved out of its second position, closes a circuit over its armature and front contact and the sequence switch contact 83 to energize the power magnet of the sequence switch 80, 65 which, together with the sequence switches

70 and 90, are common to the position of the operator on which the connecting circuit 17 appears. The power magnet of the sequence switch 80 being energized in its first or normal position, such sequence switch 70 moves under the control of its local contact 81 into its fourth position. The movement of the sequence switch 80 out of its first position opens the sequence switch contact 82 and the sequence switch contact 83 top. 75 On coming into its second position the circuit was closed over the sequence switch contact 84 and the sequence switch contact 73 to drive the sequence switch 70 out of its first and, under the control of its local contact 71, into its twelfth position. When the sequence switch 80 comes into its fourth position a circuit is closed over the sequence switch contact 85 and the sequence switch contact 92 top to start the sequence switch 85 90 95 90 in motion, which, since its local contact is only open in its first or normal position, will immediately make a complete revolution. As such sequence switch 90 passes through its eighteenth position, just before returning to its first or normal position, the sequence switch contact 92 bottom is closed and a circuit extends from the sequence switch contact 85, over sequence switch contact 92 bottom, to drive the sequence switch 95 80 into its tenth position.

When the sequence switch 60 is moved into its fourth position circuits were established over the sequence switch contacts 66, 67 and 68 for selecting and seizing an idle 100 registering and controlling equipment of such operator, such selection taking place over the switch 29 diagrammatically indicated, such selection taking place in substantially the same manner as disclosed in Patent No. 1,167,646 to F. R. McBerty.

Since it has been assumed that this operator is idle such registering and controlling equipment will have been found and seized before the sequence switch 80 reached its 110 fifth position after a complete revolution of the sequence switch 90, since the switch 29 which hunts and seizes such controlling equipment, operates at substantially the same speed as the switch 90, and the sequence switch 60 has, therefore, been driven 115 out of its fifth position in the known manner opening the sequence switch contact 66 included in the circuit of the switch 29. On coming into its tenth position, the sequence switch 80 closes the sequence switch contact 85 which again starts the sequence switch 90 to make a complete revolution. As sequence switch 90 is again passing its eighteenth position, a circuit is closed over sequence switch contacts 85 and 92 bottom 120 to drive the sequence switch 80 into its eleventh position. The sequence switch 90, therefore, when it reaches its first or normal position, finds the circuit connection closed 125 130

over the sequence switch contacts 85 and 92 top and starts on a third complete revolution. Near the completion of the third revolution of the sequence switch 90 the closure 5 of the sequence switch contact 92 bottom again causes the energization of the power magnet of the sequence switch 80 which drives this sequence switch out of its eleventh position and passing through its twelfth, 10 thirteenth, etc., positions, such sequence switch returns to its first or normal position.

It will be observed that immediately upon the seizure of the trunk 22 whereby a call is extended to the operator's position, the 15 apparatus of which is shown, and the consequent energization of the relays 19 and 26, the sequence switch 80 started in motion and immediately drove the sequence switch 70 out of its first or normal position. This 20 caused the opening of the sequence switch contacts 72, 72' and 72^x which will be maintained open until the sequence switch 70 returns to its first or normal position. These 25 sequence switch contacts as has been before noted are included in the common starting circuits of several groups of the connecting circuits located upon the position of the operator in question. So long, therefore, as such sequence switch contacts 30 remain open, no calls may be extended to such operator's position and none of the second line finders individual to the connecting circuits appearing upon such operator's position may be set in motion. When, however, 35 the time interval necessary for the operation of the sequence switch 80 into its thirteenth position, which time interval includes definitely the time required for the sequence switch 90 to make three complete 40 revolutions, has elapsed, the sequence switch 70 will be driven out of its twelfth position by the closure of the sequence switch contact 84 bottom and such sequence switch 70 will leave its twelfth position and then, 45 without stopping, move into its first or normal position in which the sequence switch contacts 72, 72' and 72^x are closed. At this time, further incoming calls which have been extended to trunks such as 22 accessible to 50 the set of second line finders connected to connecting circuits such as 17 which appear upon this operator's position, will cause the operation of such second line finders 16 in the manner hereinbefore described to extend 55 such incoming call to a connecting circuit upon such operator's position. It will, therefore, be seen that when one call has been extended to the operator's position such operator's position is maintained busy to 60 all further incoming calls until after the passage of a definite interval of time as predetermined by the adjustment, arrangement and construction of the sequence switches 70, 80 and 90. After such interval 65 of time has passed the busy guard is re-

moved from such operator's position and a second call may be extended thereto. When the second call has been extended to a connecting circuit of such operator's position, as has been described, and in consequence 70 thereof energized the relays 19 and 26 individual to the connecting circuit and second line finder to which such call has been extended, the timing apparatus is again started in motion, opening the sequence 75 switch contacts 72, 72' and 72^x and placing a busy guard upon the position and maintaining such busy guard for the predetermined interval of time, after which they are again closed and a still further 80 call may be extended to such operator's position.

In résumé it will be seen that under normal conditions upon the receipt of a call the operator's position will be maintained 85 busy for a period say of four seconds, after which time another call may be extended to her position. If, however, a call has been extended to her position which has not as yet been connected to her equipment, 90 the test guard will be maintained upon the position an increased interval which may even be as much as seven seconds, and if two calls have been connected to such operator's position, neither of which have as yet 95 been extended to her equipment, the interval may be further extended to so much, for example, as eleven seconds.

It will, of course, be understood that the time intervals referred to are given for example only and that by the rearrangement of the circuits in an obvious manner the period of time elapsing in the normal operation of the timing apparatus or in either of the abnormal cases mentioned may be so 100 modified as the traffic conditions of the particular exchange in which the apparatus is used may require. Generally, it will probably be found that if the time occupied by the timing apparatus in its normal operation is about seventy-five per cent. of the time normally required by an operator to complete her duties with regard to the average call, a considerable saving will be accomplished with a minimum delay to incoming calls.

Referring more particularly to Fig. 2, to the left are indicated a plurality of groups of first line finder switches such as the group 4, 4. The trunks connected to these line 110 finder switches are multiplied to stationary contacts in the second line finder switches such as those indicated at 16, 16, the trunks from a plurality of groups of first line finder switches appearing on each of such sets or groups of second line finder switches. As shown, the first three groups of line finder switches from the top of the figure terminate in the second line finder switches 16, 16, 16. The next three groups of line finder switches 115 120 125 130

terminate in the second line finder switches 50, 50, 50, and a third set of groups of line finder switches terminate in the second line finder switches 51, 51, 51. Associated with 5 and controlled by the trunks terminating in the second line finder switches 16 is the common starting or pilot relay 15. As has been described in connection with Fig. 1, this relay 15 is energized whenever a call 10 has been extended to a trunk of the first group and closes a circuit over the sequence switch contact 72 of the sequence switch 70 to start in motion all of the second line finder switches 16 connected to connecting 15 circuits in the several operators' positions of which three are indicated. If the sequence switch 70 on any of these operators is out of its normal position, indicating that the operator is busy, the sequence 20 switch contact 72, individual to such operator's position, will be opened and none of the second line finders 16 connected to connecting circuits of such operator's position will be started in motion. Correspondingly, 25 if the call had been extended by a first line finder to a trunk of the second group the pilot or starting relay 15', common to such group, would have been energized and the starting circuit closed to the second line 30 finders 50 connected to connecting circuits appearing upon operators' positions of such operators as are idle, over the sequence switch contact 72'. Similarly, if the call is extended by a first line finder switch to a 35 trunk of the third group, the relay 15^x will be energized and the starting circuit established will include the sequence switch contact 72^x on various operators' positions of such operators as are idle. On this figure 40 of the drawings the common control of the several relays 15, 15' and 15^x is indicated by a loop associated with the respective groups of trunks. Only the relays 18 and the sequence switch contact 62 associated 45 with the several connecting circuits indicated are shown on this figure, as by reference to Fig. 1 the complete operation with regard to any particular connecting circuit may be readily understood.

50 Referring to Fig. 2 therefore, and assuming all three operators are idle, a call extended to the trunk 22 by one of the first line finders 4 will start in motion the second line finders 16 upon all of such operators' 55 positions. When one of these second line finders 16 has selected and seized the trunk 22, the remaining second line finders 16 will be stopped in the usual manner, which need not be herein described, and the sequence switch contacts 72, 72' and 72^x of the same operator's position as the second line finder 60 16 which has selected and seized the trunk will be opened for a predetermined interval of time, as hereinbefore described. Mean- 65 while, to calls extended by any other of the

first line finders to any of the trunks shown, except the trunk in use, will still be accessible to the corresponding second line finders appearing on the remaining operators' positions. If a call has been extended 70 to all of the operators' positions shown and such operators are still busy in connection with such calls, the first of such operators whose timing apparatus has run through its cycle will have the sequence switch contacts 75 72, 72' and 72^x of her position again closed and the appropriate idle second line finders of such operator's position will be started in motion for a subsequent call in the manner hereinbefore described. 80

While each operator's position contains connecting circuits to which are connected second line finders of the different sets or groups having access to the different groups of trunks leading from the first line finders, only such second line finders as have access to the groups of trunks to which a call has been extended will start in operation, but immediately one of such second line finders has seized the trunk to which the 90 call has been extended, the entire position of such operator will be rendered busy until the timing apparatus individual to such operator's position has run through its cycle, when another call may be extended to such 95 operator's position from any of the groups of trunks to which the second line finders of such operator's position have access over such second line finders as may be idle of the appropriate set or group individual to 100 such operator's position.

In systems utilizing line finders of the type having no normal position, such as those diagrammatically illustrated in Fig. 1, the sequence switch contact 82 provided in 105 the test circuit of the second line finder and which sequence switch contact is closed only in the normal position of the sequence switch 80, prevents an idle second line finder from seizing and extending while the position is 110 busy, a call which may have been extended to the trunk 22 upon the terminals of which the brushes of such second line finder rest. The sequence switch contact 82 is multiplied to the relays 24 of each connecting circuit of 115 the position to which the sequence switch 80 is individual.

What is claimed is:

1. The combination with an operator's position of means for selecting the same and 120 extending a call thereto and apparatus actuated when a call has been extended to a trunk at said position to prevent the extension of another call to the position for a definite time interval substantially commensurate with the time employed by an operator establishing an average connection. 125

2. The combination with an operator's position of trunks extending thereto, means for extending a call to one of said trunks, 130

and apparatus responsive to the extension of a call to a trunk for rendering subsequent calls unconnectible thereto for a definite time interval after the first call has been extended to the position.

5. 3. The combination with an operator's position of means for selecting the same and subsequently extending a call to a trunk at said position, and apparatus rendered active 10 when a call has been extended to said trunk to prevent for a definite time interval the selection of such position by subsequent calls.

4. In a call distributing system, means for selecting an operator's position and extending 15 a call to a trunk at said position, means at such a position for establishing connections between calling and called lines, and means independent of such connecting means for rendering the position busy to subsequent calls for a predetermined interval after 20 the distribution of a call to said trunk.

5. In a call distributing system, means for distributing calls to trunks at an operator's position in combination with timing means 25 at said position responsive to the selection of a trunk for automatically determining the rate at which such calls may be distributed to such position independent of the condition of the connecting apparatus at such position.

6. In a call distributing system, automatic switches for distributing calls to an operator's position, automatic switches at such position for associating calls distributed 35 thereto with connecting circuits, controlling devices at said position, automatic switches for associating controlling devices with connecting circuits with which calls have been associated, and an automatic timing switch 40 started in operation when a connecting circuit at the position has been taken for use for the purpose of preventing the association

of another call with a connecting circuit at such a position until such timing switch has completed its cycle of operations.

45

7. In a call distributing system, means for distributing calls to connecting circuits at an operator's position, controlling apparatus adapted to be associated with such connecting circuits, a timing device at such position 50 responsive to the extension of a call to a connecting circuit adapted to introduce a time interval between the distribution of successive calls to the connecting circuits at such position.

55

8. In a call distributing system, calling lines, means for selecting an operator's position and extending such calling lines thereto, a position sequence switch actuated when a calling line has been extended to the position 60 to render such position non-selectable to subsequent calls, and a timing device to again actuate said position sequence switch after a predetermined time interval to again render such position selectable.

65

9. In a call distributing system, calling lines, means for selecting an operator's position and extending such calling lines thereto, a position sequence switch adapted to be driven from normal position when a 70 calling line has been extended to the position to render such position non-selectable, a timing sequence switch adapted to be driven through a cycle of operations in response to the operation of such position sequence 75 switch, and means controlled by such timing sequence switch at the termination of its cycle of operations to drive such position sequence switch back to normal and render such position again selectable.

80

In witness whereof, we hereunto subscribe our names this 2nd day of March A. D., 1917.
